FREDERICK W. HANKS, OF CLEVELAND, OHIO.

CLOSURE FOR WATER-METERS AND THE LIKE.

1,192,188.

Specification of Letters Patent. Patented July 25, 1916.

Application filed March 26, 1912. Serial No. 686,350.

To all whom it may concern:

Be it known that I, FREDERICK W. HANKS, a citizen of the United States, and a resident of Cleveland, county of Cuyahoga, and State of Ohio, have invented a new and useful Improvement in Closures for Water-Meters and the like, of which the following is a specification, the principle of the invention being herein disclosed and the best mode in which I have contemplated applying that principle, so as to distinguish it from other inventions.

The present invention, relating, as indicated, to water meters, has regard more particularly to certain features of construction of such meters, whereby a bottom wall is provided for the outer casing, which not only permits of the ready assembling and taking apart of the meter, but also will yield outwardly should the water in such casing freeze, or undue pressure from any other source be exerted within the meter.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawing: Figure 1 is a central vertical section of a meter embodying the aforesaid features of improvement; Fig. 2 is a bottom plan view of the same; Fig. 3 is a broken vertical sectional view similar to that of Fig. 1, but showing a modification in construction; and Fig. 4 is a section showing yet another modification.

The particular style of meter illustrated in the foregoing drawings is of the disk type, in which the measuring device proper takes the form of a gyratory disk 1, suitably mounted in a transversely split inner casing 2, which casing is in turn secured in an outer casing 3. The water or other fluid to be measured is designed to be admitted into this outer casing through a suitable connection 4, and thence passes into the inner casing, from which it escapes by a suitable aperture (not shown) to an outlet connection 6, incidentally actuating the gyratory disk, as will be readily understood. So far as concerns any features of improvement of

the meter mechanism proper herein shown, it should be explained that these form the subject matter of a divisional application filed June 10, 1912, Serial No. 702,678.

In the present improved construction the inner casing 2 is secured in place by means of a bottom plate or closure 7, that is directly removable so as to expose the entire interior of the outer casing and permit of the ready withdrawal of the inner casing containing the measuring device. To retain the bottom plate in place in the assembled condition of parts, a plurality of radially disposed arms 8, four in number as shown, is provided, such arms having their outer ends 9 re-curved to fit over externally directed lugs, or flanges 10, formed on the periphery of the outer casing near its bottom; while the inner ends 11 of said arms, in the form illustrated in Figs. 1 to 3 inclusive, extend into substantial contact with a central boss or lug 12 projecting downwardly from the bottom plate. This boss is internally threaded to receive a set bolt 13, by the operation of which latter either a plain washer 14 may be pressed upwardly against the inwardly extending ends 11 of the arms 8, as clearly shown in Fig. 1, or else a resilient washer 17, as shown in Fig. 3, may be thus pressed against said arm-ends. Said arms bear between their ends on suitably rounded lugs 15 on the bottom plate constituting fulcrum axes, so that, when their inner ends are thus pressed upwardly, the result is to press the bottom plate against the casing and form a water tight joint, a gasket 16 being interposed between the casing and said bottom plate. By a proper proportioning of the thickness and strength of the outer re-curved ends 9 of the arms, due provision may be made for their yielding or breaking in the event of the meter freezing, before any improper strain is imposed on the walls of the casing. However, not only does the foregoing construction possess the advantage just referred to, but in ordinary operation, to open or close the bottom it is obviously necessary to operate only a single set bolt, since thereby all the parts are drawn together. A uniform tension on the bottom plate is at the same time secured all around the periphery thereof.

Instead of a resilient washer 17, such as illustrated in Fig. 3, being interposed between the head of the set bolt and the inner

ends of the arms, it will also be understood that in the first described construction, that of Figs. 1 and 2, these arms may be made of resilient material with the same object in view, namely, to permit of a certain amount of give without breaking the arms. Such arms are furthermore desirably provided with downwardly extending projections 18 that serve as legs on which to support the meter when installed. It is a matter of indifference, as already indicated, how many such arms are utilized; for example, two might serve in a small sized meter, while four or more might be required in a large size, depending upon circumstances.

The modification illustrated in Fig. 4, relates to the arms 8 and consists of the omission of their inner ends, together with the screw 13 and washer 14 for engaging therewith. In this form, said arms no longer function as levers but simply as hooks that are snapped over the ledges 10 and lugs 15, the gasket 16 being sufficiently compressible to permit of this being done. Even where the arms are utilized in their first described form, they will possess this characteristic to a sufficient degree to hold the bottom more or less tightly in place during the assembling operation.

Each of the foregoing constructional forms of my improved closure for meters, and especially the third form illustrated in Fig. 4, is characterized by unusual simplicity, which not only renders the structure less expensive to manufacture, but as previously pointed out contributes materially to convenience of assembly both in the first instance and in case repair or examination of the interior of the meter becomes necessary after the latter is installed. Where the meter is installed it will be understood that the main casing is practically permanently secured in the pipe line; at least a great deal of difficulty and labor would be involved in detaching the same, and hence to remove the bottom would be not only annoying but frequently almost impossible if much manipulation or adjustment of parts is required. With my improved construction, however, in the first place by simply snapping the arms one at a time in place, the bottom may be temporarily secured to the casing, and thereupon, referring to the construction of arms illustrated in Figs. 1 and 3, the set bolt for engaging the inner ends of said arms may be drawn into tight engagement therewith. Finally, the "frost-proof" feature, provided by the construction of the outer re-curved ends of the arms, is extremely simple, while at the same time it permits of an unusually accurate gaging of the pressure at which the parts should yield. Furthermore, in the event of breakage actually occurring by reason of the meter freezing up, the particular arm or arms involved

represent the only damage, and may be easily and cheaply replaced, thereupon rendering the meter closure as secure as ever.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. The combination with the casing of a water meter or the like, of a closure for such casing, and means for securing said closure in place comprising one-piece arms adapted to detachably engage said casing at their outer ends, said arms being weaker than the parts of the casing so as to break under undue internal pressure and release the closure before such casing yields, a bearing on the closure for said arms, and means inside the bearing for pressing the inner portion of said arms toward the closure.

2. The combination with the inner casing and the outer casing of a water meter or the like, of a closure for said outer casing adapted to support said inner casing, and means for securing said closure in place comprising independent, one-piece arms engaging said outer casing at their outer ends, said arms being weaker than the parts of the casing so as to break under undue internal pressure and release the closure and inner casing before such outer casing yields, a bearing on the closure for said arms, and means inside the bearing for pressing the inner portion of said arms toward the closure.

3. The combination with inner casing 2 and outer casing 3, of closure 7 supporting said inner casing 2 and having bearings 15, independent, one-piece, radial arms 8 engaging said bearings and having their outer ends detachably engaging the casing 3, said arms being weaker than the parts of the casing so as to break under undue internal pressure and release said closure before such casing yields, and a screw device acting between the closure and arms inside the bearings to press the inner ends of the arms toward the closure.

4. The combination with inner casing 2 and outer casing 3 having external lugs 10, of closure 7 supporting casing 2 and having bearings 15, independent, one-piece, radial arms 8 engaging said bearings and having their outer ends detachably hooked over lugs 10, said arms being weaker than said lugs so as to break under undue internal pressure and release said closure before such casing yields, and a screw device acting between the closure and arms inside the bearings to press the inner ends of the arms toward the closure.

5. In a device of the character described,

the combination of a suitable casing; a closure therefor; and means for securing said closure in place comprising a plurality of independent, one-piece arms adapted to directly detachably engage said casing at their outer ends, said arms being weaker than the parts of the casing so as to break under undue internal pressure and release the closure before such casing yields; a screw-member threaded on said closure and adapted to draw the inner ends of said arms toward said closure, said arms bearing against the latter between their ends, and a resilient washer interposed between such inner arm-ends and said screw-member.

6. In a device of the character described, the combination of a suitable casing; a closure therefor; and means for securing said closure in place comprising a plurality of independent, one-piece, radially disposed

arms having recurved outer ends adapted to directly detachably externally engage said casing, said arms being weaker than the parts of the casing so as to break under undue internal pressure and release the closure 25 before such casing yields, a screw-member threaded on said closure and adapted to draw the inner ends of said arms toward said closure, the angle of said arms being such as to cause them to bear against said closure between their ends, and a spring washer interposed between such inner arm-ends and said member.

Signed by me this 23rd day of March, 1912.

FREDERICK W. HANKS.
